UNITED STATES PATENT OFFICE.

FITZ WILLIAM SARGENT, OF MAHWAH, NEW JERSEY, ASSIGNEE TO AMERICAN BRAKE SHOE & FOUNDRY COMPANY, OF MAHWAH, NEW JERSEY, A CORPORATION OF NEW JERSEY.

BRAKE-HEAD.

1,126,874.

Specification of Letters Patent. Patented Feb. 2, 1915.

Application filed November 11, 1914. Serial No. 371,454.

To all whom it may concern:

Be it known that I, FITZ WILLIAM SARGENT, a citizen of the United States, and a resident of Mahwah, in the county of Bergen and State of New Jersey, have made and invented certain new and useful Improvements in Brake-Heads, of which the following is a specification.

My invention relates to an improved brake head adapted to be secured to, and to hold in place, a brake shoe employed for use upon railroad and railway locomotives. As ordinarily constructed, a brake shoe is formed with a central attaching or key lug, usually about one and one-eighth inches high, and which extends through an opening formed in the brake head, a key passing through the lug and bearing on the back of the brake head to secure the shoe to the latter. It is many times found in practice that this lug is too high, especially in the case of shoes and heads used upon the driving wheel of a locomotive and interferes with the brake lever.

The object of my invention is to provide a brake head with which a shoe may be employed having a lug much shorter or lower than the standard and thus give more clearance between said lug and lever, and avoid the interference one with the other.

With these and other ends in view my invention consists in certain novel features of construction and combinations of parts as will be hereinafter fully described and pointed out in the claims.

In the accompanying drawings, Figure 1 is a top plan view of my improved brake head having a brake shoe attached thereto. Fig. 2 is a sectional view thereof taken on the line 2—2 of Fig. 1 looking in the direction as indicated by the arrow. Fig. 3 is a sectional view thereof taken on the line 3—3 of Fig. 2, looking in the direction as indicated by the arrow. Fig. 4 is a sectional view of the head detached from the shoe. Fig. 5 is a view in perspective of a portion of the head, showing the slotted back.

Referring to the drawings 10 represents a brake shoe usually made of cast iron, and

provided, if desired, with inserts 11 in the 59 wearing face thereof, and with a steel back or reinforcing plate 12 at or adjacent to the back thereof.

At the back of the shoe, and about the center of its length, is located the key lug 65 13, the ends being preferably bent and anchored under the back 12 as clearly illustrated in Fig. 3 of the drawings. This shoe is fitted to a brake head 14 provided with side walls or flanges 15 cast integral with 60 the back 16, the latter having formed therein an opening 17 through which extends the key lug 13. The walls 15 are each formed with the usual suspension eye or hub 18 by means of which the head is secured to a 65 brake lever. (Not shown.)

In order to accommodate the lower lug 13, and permit a key to pass through the same after the shoe and head have been assembled, I form in the back 16 of the latter a groove 19 of a width slightly greater than that of the key 20, this key, of course, being somewhat narrower than the opening in the lug 13 through which it passes, the floor of this groove being straight or flat. 70 rather than of the curvature of the remaining portions of the back 16 of the head. While this groove in the back of the head somewhat reduces its thickness under the key, yet it being narrower than the opening in the lug, a sufficient amount of stock is left at the sides of the groove to permit the head to retain sufficient strength to withstand any strain that might be imposed 75 upon it in service.

By thus grooving the head, the key lug is permitted to be made lower, the key itself at the same time being allowed to pass through same by removing the metal below it, and giving ample clearance room between the brake lever and lug.

What I claim is:—

1. A brake head comprising side walls and a back, said back being provided with an opening at about the center of its length 95 and a groove running longitudinally of said back for the reception of an attaching key.

2. A brake head, the back of which is

provided with a central opening and a longitudinal groove of less width than said opening.

3. A brake head the back of which is provided with a longitudinal groove extending lengthwise thereof and of less width than said back for the reception of an attaching key.

Signed at Mahwah, in the county of Bergen and State of New Jersey, this 10th day 10 of November, A. D. 1914.

FITZ WILLIAM SARGENT.
